ABSTRACT

A method for promoting color change in human hair by impregnating the hair with a solution containing at least one dialdehyde compound in combination with at least one amine containing dye and allowing the solution to remain in contact with the hair for an effective period of time to permit the desired color to develop. The use of dialdehyde promoting compounds have been found to generate the desired color in a much shorter period of time than heretofore known, and yield good development of the desired color shades.

7 Claims, No Drawings

MEANS FOR PROMOTING COLOR CHANGE IN BLEACHED OR UNTREATED HAIR

BACKGROUND OF THE INVENTION

For many years people have been dissatisfied with the natural coloration of the human hair and have sought preparations capable of modifying the colors. Numerous color modifying materials and many varied procedures for applying such materials have been developed in attempts to formulate coloring techniques which will quickly attain the desired color and to facilitate the ease of dyeing to various desired color combinations.

Generally, the various methods of dyeing hair fibers includes absorption, aggregation and bonding techniques. When direct bonding techniques are utilized on human hair, a true chemical bond is formed between the dye material and the treated hair fiber. The dye must have a reactive group which can chemically bond with one of the groups present on the hair fiber. The use of reactive dyes which form chemical bonds with the hair fibers have generally been limited due to the severe conditions which are needed to force the reaction to occur.

In general, human hair has been colored by the use of the absorption or aggregation techniques. In the absorption method the dyestuff or the vehicle in which it is introduced has an electrode affinity for the hair fiber being treated. This technique relies primarily on the charge differential between the various materials and normally can be done under conditions which are suitable for cosmetic purposes. Similarly, the aggregation method of dyeing involves a system of insolubility which is created inside the fiber to be dyed. The dye material is made fast by penetration into the fiber and the precipitation therein of the chromogenous agent.

In the absorption and aggregation methods it has been found advantageous to include a dye promoting material which enhances the dye uptake onto the hair fibers. Various chemical compounds, including certain

aromatic and aliphatic diketones, have been found useful in increasing the dye uptake of various known coloring agents. Normally, these dye promoting materials act to enhance the uptake of the hair dyeing compositions and thus reduce the time needed to form an effective dyeing of the human hair. In other cases dye promoting materials have been used to lessen the drastic conditions sometimes found necessary to form the desired coloration of the hair.

The various color promoting materials, such as the diketones mentioned above, have been limited as to color shades they will promote and the rate of promoting the dye uptake.

SUMMARY OF THE INVENTION

It has been presently unexpectedly found that dyeing

of human hair can be enhanced and promoted by impregnating hair with a pharmacologically acceptable carrier material containing one or more dialdehyde compounds of the general formula:

10 in which R represents a divalent aromatic, cycloaliphatic or aliphatic group. The dialdehyde compounds of this invention have been found to rapidly promote the dyeing of human hair by the absorption of aggregation techniques when accompanied by amine dyes suitable for these techniques.

DETAILED DESCRIPTION OF THE INVENTION

The present invention provides a composition and a process for dyeing hair which comprises impregnating the hair with a solution, emulsion, or dispersion containing one or more dialdehyde compounds described hereinbelow in combination with the necessary dye material which is to be promoted in an absorption or aggregation coloring technique.

15 A unique class of compounds for promoting of color changes human hair has been found to consist of compounds having the general formula:

20
$$\text{HC}=\text{(R)}_n\text{CH=O}$$

in which R represents a divalent aromatic, cycloaliphatic or aliphatic group and in which n equals 0 or 1.
25 When n equals 0 the dialdehyde of this invention is glyoxal. When n equals 1 a suitable divalent bridging radical is present and represented by R. Such radicals may be alkylene, arylene and cycloalkylene groupings including methylene, ethylene, propylene, butylene, pentamethylene,

tions higher than this have been, in most cases, found economically unfeasible. The additional promoting materials which may be used in combination with the dialdehydes may be in concentrations ranging from about 0.1 to about 5 per cent of the total weight of the composition.

The dialdehyde promoting compounds of this invention have been found to be suitable for most dyes found useful in the aggregation or absorption technique of dyeing human hair. The dye materials which have been found most activated by the dialdehydes herein disclosed are of the mono and polyamine containing hair dyeing compounds such as para-phenylenediamine, o-phenylenediamine, m-phenylenediamine, p-aminodiphenylamine, 2-amino-4-nitrophenol, 4-amino-2-nitrophenol, o-aminophenol, p-aminophenol, 2,4-diaminoanisole, 2,4-diaminophenol, m-tolylenediamine and the like. The dye concentration may be from about 0.01 to about 5 per cent of the composition, preferably about 0.1 to 0.5 percent.

The use of the dialdehyde compound herein above described has been found to yield extremely fast color treatment when used in combination with a dyeing material. Normally, the hair being treated may be contacted with the combination of a hair dye and the dialdehyde promoter for less than 5 minutes to yield the desired color change. Normally, the desired color is attained in from about 1 to about 4 minutes.

The process of this invention may be carried out by contacting the hair first with a solution, dispersion or emulsion containing the dialdehyde and allowed to remain on the hair for a time sufficient to permit penetration of the hair. Normally from about 1 to about 5 minutes in duration is sufficient. The hair is then permitted to be treated with a solution containing the desired dye material. Alternately, the hair dye and the dialdehyde material may be applied to the hair in the same solution. When the dye is applied in this manner, it normally will cause the desired color change within a time of less than 5 minutes.

The hair dye material in combination with the dialdehyde promoter herein disclosed is rinsed free of the hair after producing the desired color change. These spent materials may be washed free with water or with any commercially available shampoo to allow the hair to have the dyed color within a relatively short period of time and to produce a dyed hair which has remarkable fastness and reproducible results.

It has also been found that shades of silver to black which have heretofore been found unsuitable for absorption and aggregation hair coloring techniques are suitably promoted when a dialdehyde and a dye such as para-phenylenediamine and the like are used.

The dialdehyde material in combination with the dye producing compound is generally applied to the hair in the form of an aqueous solution, dispersion or emulsion. Any pharmaceutically acceptable carrier base such as water or an aqueous shampoo solution may be used as a carrier material for application of the essential ingredients on the hair. The essential ingredients in combination with such carrier materials are allowed to remain on the hair for a length of time necessary for producing the desired color change. Such time is normally from about 1 to about 4 minutes and normally less than 5 minutes in time has been found acceptable. The hair is then rinsed free of the spent materials with warm water and may be washed with any commercial

shampoo in order to remove residual materials. Additional solvents, such as alcohols, preferably lower alcohols, such as methanol, ethanol, isopropanol, and the like alone or in combination with polyols, such as glycerol and the like may be incorporated into the pharmaceutically acceptable carrier material.

In addition, various fillers, buffers, additional solvents, detergents, perfumes, stabilizers and the like may be used in combination with the solution applied to the hair. The use of these various additional ingredients will depend upon the specific mode of application, the specific type of hair texture and dyestuff being used as well as other variables known to those skilled in the art.

The following examples are set forth for the purposes of illustration only and are not to be construed as limitations on the present invention except as set forth in the appended claims.

EXAMPLE I

Locks of blond hair which were previously washed with a commercial shampoo, rinsed clean and dried were treated with an aqueous solution containing 1 per cent orthophthalaldehyde. One of the treated locks of hair was washed free of the solution after 5 minutes and another treated lock was washed free of solution after 10 minutes. Neither sample showed color change.

EXAMPLE II

A lock of blonde human hair is treated with an aqueous solution containing 0.2 parts of p-aminodiphenylamine and 0.2 parts of o-phthalaldehyde in 100 parts of solution. The solution was allowed to remain on the hair for 4 minutes and then rinsed with warm water. The resultant hair has a rich black color. A lock of hair was similarly treated with an aqueous solution containing 0.2 parts of p-aminodiphenylamine per 100 parts of solution. The resultant hair has a pale brown color.

EXAMPLE III

A lock of human hair is treated with an aqueous alcoholic (80:20) solution containing 0.2 parts of p-phenylenediamine and 0.2 parts o-phthalaldehyde. The solution is allowed to remain on the hair for 5 minutes and then rinsed with warm water. The resultant hair has a rich black color.

EXAMPLE IV

An emulsion carrier comprising

Glycerol monostearate	8.0
Sodium lauryl sulfate	0.25
Propyl paraben	0.1
Methyl paraben	0.15
Water	q.s.

is mixed with 0.2 parts of p-diaminoanisole and 0.2 parts of p-phthalaldehyde. The emulsion thus formed is applied to human blonde hair and allowed to remain for 4 minutes. The emulsion is then rinsed off with a commercial shampoo. The color of the hair is black. When a same solution is allowed to remain on the hair for 1 minute, a blue-gray color is attained.

EXAMPLE V

An aqueous solution containing 0.2 parts of p-aminophenol dye with 0.2 parts 1,3-propyldialdehyde

is applied to a lock of human hair and allowed to remain for 4 minutes. The hair is then rinsed with warm water and a commercial shampoo. The resultant hair had a warm brown coloration.

In comparison, an aqueous solution containing 0.2 parts of p-aminophenol dye is applied to human hair as described above. Only a brown tinge resulted.

wherein n may be 0 or 1 when n equals 1, R represents a divalent radical selected from the group consisting of methylene, ethylene, propylene, butylene, pentamethylene,

It will be understood that it is intended to cover all changes and modifications of the examples of the invention herein chosen for the purpose of illustration which do not constitute departures from the spirit and scope of the invention.

What is claimed is:

1. An aqueous hair dyeing composition comprising from about 0.05 to about 5 percent of a dialdehyde having the general formula:

wherein n may be 0 or 1 and when n equals 1 R represents a divalent radical selected from the group consisting of methylene, ethylene, propylene, butylene, pentamethylene,

and from about 0.01 to about 5 percent of at least one mono or polyamine dye suitable for aggregation or absorption techniques of dyeing human hair allowing the composition to remain on the hair for a period of time to effect the desired color and rinsing said spent composition from the hair.

20 4. The method according to claim 3 wherein the dialdehyde is selected from the group consisting of o-phthalaldehyde and p-phthalaldehyde.

5. The method according to claim 3 wherein the composition is allowed to remain on the hair for a time of less than 5 minutes to yield the desired color change.

30 6. The method according to claim 5 wherein the composition is allowed to remain on the hair for a period of from about 1 minute to about 4 minutes.

7. A method of promoting color change in human hair comprising first applying to the hair a promoting amount of an aqueous composition containing from

and from about 0.01 percent to about 5 percent of at least one mono or polyamine dye suitable for absorption or aggregation techniques of dyeing human hair.

2. The composition according to claim 1 wherein the dialdehyde is selected from the group consisting of o-phthalaldehyde and p-phthalaldehyde.

3. A method of promoting color change in human hair comprising applying to the hair an effective coloring amount of an aqueous composition containing from about 0.05 to about 5 percent of a dialdehyde compound having the general formula:

about 0.05 to about 5 percent based on the total weight of the composition of a dialdehyde compound of the formula:

wherein n may be 0 or 1 and when n equals 1 R represents a divalent radical selected from the group consisting of methylene, ethylene, propylene, butylene, pentamethylene,

allowing said composition to remain on the hair for a time sufficient to permit penetration of the hair by the dialdehyde compound, applying an aqueous solution containing from about 0.01 to about 5 percent based on the total weight of the solution of at least one mono

or polyamine dye suitable for aggregation or absorption techniques of dyeing human hair, allowing the composition to remain on the hair for a period of time to effect the desired color change and rinsing said spent composition and solution from the hair.
